COFFEE PERCOLATOR

Dominic J. De Fano, Palatine, and Robert I. Kallman, Elburn, Ill., assignors to Sunbeam Corporation, Chicago, Ill., a corporation of Illinois

Filed July 13, 1966, Ser. No. 3,064

Term of patent 14 years

(Cl. D44—26)

FIG. 1 is a perspective view of a coffee percolator showing the new design;

FIG. 2 is a rear elevation view of the coffee percolator; FIG. 3 is a front elevation view thereof; and

FIG. 4 is a top plan view thereof.

The dominant features of the design are shown in full lines.

We claim:

The ornamental design for a coffee percolator, as shown and described.
